(57) **CLAIM**

The ornamental design for a code scanning gun, as shown
and described.

DESCRIPTION

FIG. 1 is a front, right, and top perspective view of a code
scanning gun;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of
the code scanning gun that form no part of the claimed
design.

1 Claim, 7 Drawing Sheets
